UNITED STATES PATENT OFFICE

98,498

DESIGN FOR A MINIATURE POST OFFICE BUILDING UNIT

Orley D. Clements, Elmwood, Nebr.

Application June 18, 1935, Serial No. 57,320

Term of patent 7 years

To all whom it may concern:

Be it known that I, Orley D. Clements, a citizen of the United States, residing at Elmwood, in the county of Cass and State of Nebraska, have invented a new, original, and ornamental Design for a Miniature Post Office Building Unit, of which the following is a specification, reference being had to the accompanying drawing, forming part thereof.

I claim:—

The ornamental design for a miniature post office building unit as shown.

ORLEY D. CLEMENTS.
